UNITED STATES PATENT OFFICE.

HARRY LUTHER YOUNG, OF PUEBLO, COLORADO.

RAILWAY-SWITCH CONSTRUCTION.

No. 826,462.

Specification of Letters Patent.

Patented July 17, 1906.

Application filed March 21, 1906. Serial No. 307,167.

To all whom it may concern:

Be it known that I, HARRY LUTHER YOUNG, a citizen of the United States, residing at Pueblo, in the county of Pueblo and State of Colorado, have invented new and useful Improvements in Railway-Switch Construction, of which the following is a specification.

My invention relates to railway-switches, and particularly to those of city or suburban roads, the movable element or switch-point of which is apt to become clogged or impeded by the accumulation of dirt and other debris.

The principal object of my invention is to provide a rigid, durable, and efficient support for the movable switch-point and one which will be self-cleaning—that is, will be automatically cleaned by the movement of the switch-point in its normal operation. My construction prevents the accumulation of dirt, &c., both beneath the movable switch-point and also at its sides.

An embodiment of the invention is illustrated in the accompanying drawings, in which—

Figure 1 is a perspective view of the railway-switch. Fig. 2 is a detail showing the attachment of the operating-rod to the switch-points. Fig. 3 is an enlarged detached view in perspective of the point-support and rail. Fig. 4 is a similar view of the supporting-chair; and Fig. 5 is a transverse section through the complete structure, showing also a pit for the reception of the dirt or debris.

Referring to the drawings, A is a switch-rail having an upright tread portion a, arranged in alinement with and adapted to form a continuation of the track-rail B. Switch-rail A has also a base portion a', adapted to support the movable switch-point C, pivoted at c, and is provided with bolt-holes a² or other suitable means for attachment to its supporting guard or chair D. This guard or chair D is spiked to the cross-ties E and forms massive and rigid support for the switch.

Base portion a' of switch-rail A is slotted, as at a³, to receive the operating-rod c', which is pivotally connected to the switch point or points C by pin c² and provided at one end with any suitable means c³ for attachment to the switch-actuating devices. (Not shown.)

In Figs. 1 and 2 I have shown two movable switch-points for a single switch; but it will

be understood that this is not essential, as only one may be employed, if preferred.

In order to prevent accumulation of dirt about the switch-points, I provide the base portion a' of switch-rail A with a set of slots or openings a⁴, preferably arranged transversely and having a flat substantial strip a⁵ between them for the efficient support of switch-point C. These strips a⁵ being flat will wear for a long time. In order to prevent clogging at the sides of the switch-point by dirt which fails to drop through the base slots or openings a⁴, I provide the upright tread portion a also with a set of openings a⁶, which are staggered with relation to openings a⁴, and each one is opposite one of the flat strips a⁵, so that dirt which is pushed laterally along the flat strips a⁵ will pass out of openings a⁶ and will not impede the movement of the switch-point. Openings a⁶ may be arch-shaped, as shown, or they may have any desired shape.

The guard or chair D is provided with base-openings d', which register with openings a⁴ of switch-rail A and has guard-flanges d d². Between these flanges and switch-rail A a space d³ is allowed through which dirt may pass from said switch-rail A. The upper edge of flange d² projects toward and engages the side of tread portion a of the switch-rail to form a brace or support therefor. Adjacent flange d² I provide a series of openings d⁴ in the base of guard or chair D, which openings are staggered with respect to openings d', so as to come opposite openings a⁶ of the switch-rail A. Beneath the whole structure is provided a suitable pit d⁵, from which discharged dirt may be removed.

Having described my invention, what I claim as new, and desire to secure by Letters Patent of the United States, is—

1. In a railway-switch structure, the combination with a movable switch-point, of a supporting-base therefor provided with discharge-openings and having a lateral flange, said lateral flange being provided with discharge-openings staggered with relation to said supporting-base openings, substantially as described.

2. In a railway-switch structure, the combination with a movable switch-point, of a supporting-base therefor provided with discharge-openings with substantially flat supporting portions therebetween, a lateral flange for said base provided with discharge-openings staggered with relation to said base-

- openings and opposite said supporting portions, substantially as described.
3. In a railway-switch structure, the combination with a movable switch-point, of a supporting-base therefor provided with discharge-openings and having an upright rail-tread portion provided with discharge-openings staggered with relation to said supporting-base openings, substantially as described.
4. In a railway-switch structure, a combined rail and base having a supporting-base portion and a tread portion formed with sets of discharge-openings staggered with relation to each other, and a movable switch-point upon said base portion adapted to expel dirt or other debris which fails to fall through said base-portion openings, through said tread-portion openings, substantially as described.
5. In a railway-switch structure, the combination with a switch-point-supporting base provided with discharge-openings and having a lateral flange also provided with discharge-openings, a switch-point pivoted for movement upon said supporting-base and an operating-rod pivotally connected to said switch-point, said supporting-base being provided with a channel to receive said rod, substantially as described.
6. In a railway-switch structure, the combination with a movable switch-point, of a supporting-base therefor provided with discharge-openings and having an upright tread-flange also provided with discharge-openings, and a chair for said supporting-base provided with discharge-openings to cooperate with said supporting-base and tread-flange openings, substantially as described.
7. In a railway-switch structure, the combination with a movable switch-point, of a supporting-base therefor provided with discharge-openings and having an upright rail-tread portion also provided with discharge-openings, and a chair having a flange formed to engage and brace said upright rail-tread portion, said chair being formed with openings to coöperate with said discharge-openings, substantially as described.
8. In a railway-switch structure, the combination with a movable switch-point, of a supporting-base therefor provided with discharge-openings and having an upright rail-tread portion also provided with discharge-openings, and a chair having a flange formed at one side to engage and brace said upright rail-tread portion and a second flange at the other side to constitute a guard-rail, said chair being formed with openings to coöperate with said discharge-openings, substantially as described.
9. In a railway-switch structure, the combination with a movable switch-point, of a supporting-base therefor provided with discharge-openings and having a lateral tread-flange also provided with discharge-openings, and a chair formed with a set of openings registering with said base-openings and another set registering with said tread-flange openings, substantially as described.
10. In a railway-switch structure, the combination with a movable switch-point, of a supporting-base therefor provided with discharge-openings and having a tread-flange, said tread-flange being provided with discharge-openings staggered with relation to said supporting-base openings, and a chair formed with one or more upright flanges and with discharge-openings registering with said base and tread-flange openings, substantially as described.

In testimony whereof I have signed my name to this specification in the presence of two subscribing witnesses.

HARRY LUTHER YOUNG.
